(57) **CLAIM**

The ornamental design for glasses for watching stereoscopic images, as shown and described.

DESCRIPTION

FIG. 1 is a top-front side perspective view of glasses for watching stereoscopic images showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom-rear side perspective view thereof;

FIG. 9 is a perspective view thereof, shown in a closed position; and,

FIG. 10 is a perspective thereof, shown with environment in a state of use.

The broken lines shown in FIG. 10 are included for the purpose of illustrating environmental structure and portions of the article and form no part of the claimed design.

1 Claim, 10 Drawing Sheets
